SHOE LAST

George Clausing, Portsmouth, Ohio, assignor to
Vulcan Corporation, Portsmouth, Ohio

Application January 17, 1947, Serial No. 722,557

10 Claims. (Cl. 12—135)

1

The present invention relates to improvements in shoe lasts and has for its principal object the provision of a novel device for releasing relatively movable shoe last parts that are locked in expanded position, so that said parts may be readily collapsed for removal of the finished shoe therefrom.

The invention is illustrated in conjunction with the type of shoe last disclosed in my Patent No. 2,065,655 issued December 29, 1936, wherein expansion of the last occurs along a straight line and the last parts are locked in expanded position by the overcenter position of a toggle means pivotally connected to each last part. In practice considerable difficulty has been experienced in tripping or releasing the lock for this type of last because the lock is inaccessibly positioned between the last parts and is also removed to the interior part of the last to preclude its contact with the shoe. Furthermore the lock maintains the last parts in expanded condition against considerable compressive forces set up in the parts by the longitudinal stretching of the shoe on the last and this force makes it difficult to readily trip the last lock even though a suitable releasing tool is used in the prescribed manner.

It is therefore another object of the invention to provide in a shoe last having relatively expandable fore and heel parts a positive device for operating a lock means which releasably holds the parts in expanded position, said device being readily accessible through the top of one of the said last parts.

Another object of the invention is to provide in an expandable shoe last a novel release means for a toggle lock that is adapted to maintain the last parts in expanded position, said release means being operable through a jack post receiving opening formed in one last part.

A further object of the invention is to provide in a shoe last having relatively expandable parts that are held in expanded position by a pivoted lock means, a novel lock release means which is pivoted to one last part and has a free end extending into the bottom portion of a jack post receiving opening formed in said last part and disposed therein for release movement in the longitudinal direction of the opening.

Other objects attained by my invention will be apparent from the following specification and claims which illustrate a preferred embodiment of the invention.

In the drawing:

Fig. 1 is a side elevation of the shoe last in ex-

2

panded condition, parts being broken away to disclose the operating parts therefor.

Fig. 2 is an elevational view of the shoe last similar to that of Fig. 1 showing the last in collapsed position.

Fig. 3 is a fragmental, top plan view of the shoe last.

Fig. 4 is a side elevation of the shoe last in operative position upon a shoe jack, the shoe being removed therefrom.

The last comprises a fore part 5 and a heel part 6 mounted on a pair of spaced, longitudinally extending guide rods 7 and 8 for relative expandable movement. As illustrated in the drawings the guide rods 7 and 8 are anchored by any suitable means in the heel part 6 and are received in longitudinally extending bores 9 and 10 respectively formed in the fore part 5.

A suitable lock means 11 connects the parts 5 and 6 of the last and preferably takes the form of a toggle having at least one member 12 pivoted to the heel part 6 by a transverse pin 13 anchored in the said part. The member is positioned for rocking movement in a suitable rout 14 formed centrally in the heel part. The forward end of the member 12 is pivotally connected between links 15 and 16 by a transverse pin 17, the free ends of said links being pivotally connected to the fore part of the last by transverse pin 18. The links 15 and 16 are positioned for pivotal movement within a rout 19 formed in the fore part said rout having a transverse dimension just wide enough to permit free movement of said links therein. The last parts are locked in the expanded position illustrated in Fig. 1 by the over center position of the member 12 and links 15 and 16 whereby upon compressive forces being exerted on the last parts the lock parts will be forced against the bottoms of the routs 14 and 19 to preclude collapse of the parts.

The adjacent vertical faces 20 and 21 of the last parts 5 and 6 respectively have formed therein complementary arcuate recesses 22 and 23 which form an expanding tool receiving recess 45 when the last is in contracted position illustrated in Fig. 2.

In the above device which is old I provide a novel means for releasing the lock 11 when said lock is operative to hold the parts in their expanded position. To this end I provide an opening 24 formed preferably in the heel part of the last and extending vertically into said part from the top 25 thereof. The bottom portion of the opening communicates with the rear portion of the rout 14 and as most clearly illustrated in Fig.

4 said opening serves also as a jack post receiving recess for supporting the last in operative position whilst carrying out shoe making operations thereon.

A release means is associated with at least one pivoted member of the lock 11 and preferably takes the form of an arm 26 integrally formed on the rear part of the member 12 and extending beyond the lock means in a longitudinal direction and into the bottom portion of the opening 24 for rocking movement in the direction of the longitudinal dimension of said opening.

As illustrated in Fig. 4 the jack post 27 for supporting my last upon a suitable work piece has a shoulder 28 formed thereon which contacts the top surface 25 of the heel part and holds the upper end of the post out of contact with the release arm 26 for the lock.

In operation therefor my last is moved to the collapsed position indicated in Fig. 2 before it is inserted in an unfinished shoe. A suitable tool 29 is then inserted in the opening formed by the recesses 22 and 23 and upon endwise pressure being exerted thereon said tool expands the toggle and moves the last parts to their expanded position indicated in Fig. 1 wherein the toggle maintains the parts in said position against the compressive forces made by the expansion of the shoe by the last. The last is then mounted upon the jack 27 in the position illustrated in Fig. 4 and the shoe making steps are then performed on the unfinished shoe. Thereafter the last is removed from the jack post and a suitable tool 30 inserted in the jack receiving opening 24 of the last and upon the exertion of a suitable endwise force on the tool the lock release arm 26 will be moved downwardly thereby rocking the member 12 on its pivot 13 and moving the lock beyond dead center. The last parts may then be moved to their collapsed position, illustrated in Fig. 2, for the removal of the finished shoe and for its insertion into the next unfinished shoe.

What is claimed is:

1. A shoe last comprising relatively expandable fore and heel parts, a pivoted lock means for securing the last parts in expanded position, an opening formed in one last part, and a releasing arm extending from the lock means into the opening.

2. A shoe last comprising relatively expandable fore and heel parts, a pivoted lock connected to each last part for maintaining said parts in expanded position, an opening formed in one last part, and a lock release means pivotally connected to the said part and extending beyond the lock into the said opening.

3. A shoe last comprising relatively expandable fore and heel parts, a pivoted lock connected to said last parts and adapted to maintain said parts in expanded position, an opening formed in one last part, and a release arm fixed to the lock and extending into the said opening.

4. A shoe last comprising relatively expandable fore and heel parts, a lock means for securing said last parts in expanded position and having at least one member pivotally mounted in one last part, an opening formed in said last part, and a release arm fixed to the member and extending into said opening.

5. A shoe last comprising relatively expandable fore and heel parts, a lock means for securing said last parts in expanded position and having at least one member pivotally mounted in one last part, a jack post receiving opening formed in said last part, and a release arm fixed to the member and extending into said opening.

6. A shoe last comprising relatively expandable fore and heel parts, a lock means for securing said last parts in expanded position and having at least one member pivotally mounted in one last part, a jack post receiving opening formed in said last part, and a release arm fixed to the member and extending into the opening for reciprocating movement therein in the longitudinal direction of the opening.

7. A shoe last comprising relatively expandable fore and heel parts, a lock means for securing said last parts in expanded position and having at least one member mounted for rocking movement in one last part, a jack post receiving opening formed in said last part, and a release arm fixed to the member and extending into the opening for reciprocating movement therein in the longitudinal direction of the opening.

8. A longitudinally expandable shoe last comprising relatively movable fore and heel parts, guide means connecting said parts and positioned longitudinally of the last, a toggle means for securing said last parts in expanded position, a jack post receiving opening formed in one last part, and a release arm fixed to the toggle and extending into the opening for reciprocating movement therein in the longitudinal direction of the opening.

9. A longitudinally expandable shoe last comprising relatively movable fore and heel parts, guide means connecting said parts and positioned longitudinally of the last, a pair of links freely pivoted together at one of their ends and at their other ends pivoted respectively to the fore and heel parts, a jack post receiving opening formed in one last part, and a release arm fixed to one link and extending into said opening for reciprocating movement therein in the longitudinal direction of the opening.

10. A longitudinally expandable shoe last comprising relatively movable fore and heel parts, guide means connecting said parts and positioned longitudinally of the last, a pair of links freely pivoted together at one of their ends and at their free ends pivoted respectively to the fore and heel parts, a jack post receiving opening formed in one last part, a release arm formed on the free end of one link and extending in a longitudinal direction beyond said link and into the bottom of the jack post opening.
